UNITED STATES PATENT OFFICE.

RUDOLPH CONRADER, OF ERIE, PENNSYLVANIA.

PUMP.

1,067,314.

Specification of Letters Patent.

Patented July 15, 1913.

Application filed January 23, 1911. Serial No. 604,009.

To all whom it may concern:

Be it known that I, RUDOLPH CONRADER, a citizen of the United States, residing at Erie, in the county of Erie and State of Pennsylvania, have invented new and useful Improvements in Pumps, of which the following is a specification.

This invention relates to pumps and consists in certain improvements in the construction thereof as will be hereinafter fully described and pointed out in the claims.

More particularly, the invention relates to that type of pumps used in Artesian wells, especially oil wells, and is directed more particularly to devices for connecting the sucker rod with the standing valve so that the standing valve may be lifted for renewal, repair or for draining the pump.

The invention is illustrated in the accompanying drawings as follows:

Figure 1 shows a cross section on the line 1—1 in Fig. 2. Fig. 2 shows a central vertical section through the plunger and standing valve. Fig. 3 a transverse section on the line 3—3 in Fig. 2. Fig. 4 a central section through the plunger. Fig. 5 a perspective view of the trunnion and connected parts at the top of the well. Fig. 6 a central section through the standing valve and working barrel showing the standing valve in an elevated position. Fig. 7 a central section through the working barrel and adjacent parts and showing the actuating means at the top of the well.

1 marks the strainer common to pumps of this class, 2 an extension on the working barrel, and 3 the working barrel proper or that part of the working barrel having the working surfaces. The extension 2 has the standing valve socket 4 in which is placed the standing valve 5, the valve having the usual packing 6 which is to effect a joint. The standing valve crown 7 forms the usual cage for the standing valve check 8.

The plunger 9 as shown is tubular and simply provided with metal surfaces which operate in conjunction with the surface of the working barrel. It has the crown 10 in which is arranged the spider 11 forming the connecting means for the sucker rod connection 12. A plunger valve 13 is secured to the sucker rod connection and operates on the valve seat 14 at the bottom of the crown 10. The sucker rod connection has the shoulder 15 which limits the downward

movement terminating in the screw 16 on which the sucker rod 17 is screwed. In the operation of the pump with this type of plunger valve, the operation of the plunger valve does not depend on the fluid pressure, but on the downward stroke of the sucker rod, the valve is forced downward away from this seat, the frictional engagement of the plunger with the working barrel resisting this movement. The collar 15 permits the downward movement of the sucker rod connection 12. On the return stroke of the pump, the sucker rod connection slides upwardly through the spider 11 until the plunger valve seats. This seating of the valve not only closes the valve but also forms the lifting connection with the plunger so that with a further movement of the sucker rod, the plunger is lifted.

It is desirable to lift the standing valve for the purpose of renewal or repair and also for the purpose of draining the pump. I provide a screw connection between the sucker rod connection and the standing valve by means of which the standing valve may be connected with the sucker rod connection so as to be lifted. I prefer to form this connection with a yielding screw so that as the parts are brought together, the screw threads are not injured and yet the engagement of the screw practically assured. A rod 18 is screwed into the top of the standing valve crown 7 and locked in position by the jam nut 19. A fitting 20 is screwed on to the top of the rod, this fitting being telescopically arranged within the plunger 9. The fitting has the side guide pieces 21 connected by the perforated transverse portion 22 in which is arranged a screw 23. This screw is adapted to engage the screw 24 in the valve 13 as the sucker rod connection is lowered into engagement with the screw 23. The screw 23 has the head 25 which slides between the guides 21 and is locked by the guides against rotation. A spring 26 is arranged within the guides and is tensioned against the head of the screw 23. The rod 18 has a small projection 27 which extends within the spring to lock it in position and the head 25 has the projection 28 which extends within the spring for the same purpose.

When it is desired to couple the sucker rod connection with the standing valve, the plunger is lowered and the sucker rod is

turned so as to rotate the sucker rod connection 12. As this connection and valve 13 are lowered, the screw 23 yields so as to prevent any jamming or injury of the threads. At the same time, the spring 5 forces the screw upwardly so that the entry of the thread is assured. The yielding movement of the screw 23 is sufficient to allow the lower end of the valve 13 to contact the top of the fitting 20 so that regardless of how the plunger and sucker rod connection may be lowered, the screw cannot be injured.

In order to bring the screw 24 into engagement with the screw 23 it is necessary to lower the plunger to a position on the nut 19 as shown in Fig. 4. As the parts are screwed together, the valve 13 will be secured below the seat 14 and as the parts 15 are lifted the plunger is prevented from dropping down to close the valve 13 by reason of the fact that it is resting on the nut 19.

The tube 31 is connected by the coupling 25 32' to the working barrel 3 in the usual manner and extends to the top of the well. The sucker rod 17 terminates with the usual polished rod 32. This polished rod is attached to the polished rod adjuster. The 30 rod extends into the body 34 and through the eye bolt 35, the eye bolt being arranged in the body. The eye bolt has the projection 36 and the nut 37 is arranged on this projection. By means of the nut 37 pressure 35 may be exerted on the eye bolt so as to clamp the rod in place. The polished rod 32 extends through the eye bolt and as the eye bolt is forced sidewise is clamped in position. This has the ordinary construction 40 for adjusting the polished rod. A screw thread socket 38 is arranged in the top of the adjuster and the pipe 39 is screwed into this socket. A portion at least of the pipe 39 is screw threaded and is 45 screwed through the head 40 of the trunnions 41. The trunnions are arranged in the usual bearings on the walking beam 42.

When it is desired to lift the standing valve, the walking beam is stopped at its 50 lowest position and the pipe 39 on sucker rod adjuster is screwed down thus lowering the plunger to a position where the screw threads 24 of the valve 13 will engage the screw 23. As the sucker rods are turned down, it will be noted that the sucker rod connection 12 turns in the plunger so as to relieve the plunger of the turning action. The pipe 39 is preferably provided with a nut 43 for indicating the position where the 55 sucker rod connection is brought into engagement and also with the nut 44 for indicating the clamping position and for locking the pipe in adjustment in the trunnion head.

60 65 It is often desirable to simply lift the

standing valve and discharge the liquid from the tube so as to clean the valve surfaces or flood the well. By making the extension 2 larger than the standing valve and of sufficient length to form a bypass 70 around the standing valve when the standing valve is lifted, this can be readily accomplished without lifting the plunger from the working barrel. In Fig. 7 the plunger is lowered and the sucker rod connection 75 has been screwed into engagement with the screw 23. In Fig. 6 the standing valve as shown is lifted into the extension 2. It will be readily seen that the liquid can pass around the standing valve and be discharged. It will also be noted that when these parts are in engagement, the valve 13 is opened so that the liquid from the tube can pass through the plunger.

I prefer to arrange a flange nut 30 in the 80 bottom of the plunger forming an internal shoulder which will engage the bottom of the fitting 20 and thus lift the standing valve. This scheme of lifting the standing valve can be utilized should the screw connection become disarranged, or where it is 85 not important to drain the tubing.

I do not claim broadly in this application a yielding connection between the plunger and standing valve or a yielding bolt on the 90 plunger or standing valve as these features form the subject matter of applications #604,007 and #604,008 filed on even date herewith.

What I claim as new is:

1. In a pump, the combination of a working barrel; a plunger in the barrel; a sucker rod connection movable relatively to the plunger; a plunger valve actuated by the connection; a standing valve; devices for connecting the sucker rod connection with the standing valve and for maintaining the plunger valve open; and devices connecting the standing valve and sucker rod connection. 100

2. In a pump, the combination of a working barrel; a plunger in the barrel; a sucker rod connection movable relatively to the plunger; a plunger valve actuated by the connection; a standing valve; and devices comprising a yielding screw for connecting the sucker rod connection with the standing valve. 105

3. In a pump, the combination of a working barrel; a plunger in the barrel; a sucker rod connection movable relatively to the plunger; a plunger valve actuated by the connection; a standing valve; and devices comprising a yielding screw carried by the standing valve for connecting the sucker rod connection with the standing valve. 120

4. In a pump, the combination of a working barrel; a plunger in the barrel; a sucker rod connection movable relatively to the plunger; a plunger valve actuated by the 125

130

110

115

120

125

connection; a removable standing valve; and devices comprising a screw normally detached and arranged within the plunger for connecting the sucker rod connection 5 with the standing valve.

5. In a pump, the combination of a working barrel; a plunger in the barrel; a sucker rod connection movable relatively to the plunger; a plunger valve actuated by the 10 connection; a standing valve; devices comprising a pin extending from the standing valve and telescoping the plunger; and a yielding connection between the plunger and the pin.

15. 6. In a pump, the combination of a working barrel; a plunger in the barrel; a sucker rod connection movable relatively to the plunger; a plunger valve actuated by the connection; a standing valve; devices comprising a rod extending from the standing valve and telescoping the plunger; and a yielding connection comprising a fitting arranged within the plunger and a screw 20 yieldingly mounted in the fitting for connecting the sucker rod connection with the 25 standing valve.

7. In a pump, the combination of a working barrel; a plunger in the barrel; a sucker rod connection movable relatively to the plunger; a plunger valve actuated by the 30 connection; a standing valve; devices comprising a pin extending from the standing valve and telescoping the plunger; a fitting on the pin within the plunger; a screw 35 yieldingly mounted in the fitting; and a screw on the sucker rod connection for engaging the yielding screw for connecting the sucker rod connection with the standing valve.

40. 8. In a pump, the combination of a working barrel; a plunger in the barrel; a sucker rod connection movable relatively to the plunger; a plunger valve actuated by the connection; a standing valve; devices comprising a pin extending from the standing 45 valve and telescoping the plunger; a yielding connection between the plunger and the pin; and means on the plunger for engaging the pin to lift the standing valve.

50. 9. In a pump, the combination of a working barrel; a standing valve in the working barrel; a hollow plunger in the working barrel having a valve seat at the top thereof; a sucker rod connection slidably mounted at the top of the plunger; a plunger valve on the sucker rod connection for operating upon the said valve seat; a rod extending from the standing valve and telescoping the plunger; a fitting on the rod; a screw yieldingly mounted on the fitting; and a screw 55 in the plunger valve for engaging said screw in the fitting.

10. In a pump, the combination of a working barrel; a hollow plunger in the 60 working barrel; a standing valve; a rod on

the standing valve extending into the plunger; and means comprising screws normally detached and arranged within the plunger for connecting the rod and plunger.

11. In a pump, the combination of a 70 working barrel; a hollow plunger in the working barrel; a standing valve; a rod on the standing valve extending into the plunger; means comprising screws arranged within the plunger for connecting the rod 75 and plunger, and a second means for lifting the standing valve with the plunger.

12. In a pump, the combination of a working barrel; a standing valve in the working barrel; a plunger in the working 80 barrel; a sucker rod connection rotatively mounted in the plunger; and a screw connection between the sucker rod connection and the standing valve.

13. In a pump, the combination of a 85 working barrel; a standing valve in the working barrel; a plunger in the working barrel; a sucker rod connection rotatively mounted in the plunger; and a yielding connection comprising a yielding screw between 90 said sucker rod connection and standing valve.

14. In a pump, the combination of a working barrel; a standing valve in the working barrel; a plunger in the working 95 barrel; a sucker rod connection movable axially and rotatively relatively to the plunger; a plunger valve actuated by said sucker rod connection; and a screw connection between the sucker rod connection and the 100 standing valve.

15. In a pump, the combination of a working barrel; a standing valve in the working barrel; a plunger in the working 105 barrel; a sucker rod connection movable axially and rotatively relatively to the plunger; a plunger valve actuated by said sucker rod connection; and a screw connection between the sucker rod connection and the standing valve, said screw connection comprising a yielding screw.

16. In a pump, the combination of a working barrel; a standing valve in the working barrel; a plunger in the working 115 barrel; a sucker rod connection movable axially and rotatively relatively to the plunger; a plunger valve actuated by said sucker rod connection; and a screw connection between the sucker rod connection and the standing valve, said connection comprising 120 a yielding screw arranged within the plunger.

17. In a pump, the combination of a working barrel; a standing valve in the working barrel; a plunger in the working 125 barrel; a sucker rod connection movable axially and rotatively relatively to the plunger; a plunger valve actuated by said sucker rod connection; and a screw connection between the sucker rod connection and the 130

standing valve, said connection comprising a yielding screw arranged within the plunger and carried by the standing valve.

18. In a pump, the combination of a working barrel; a standing valve in the working barrel; a hollow plunger in the working barrel; a sucker rod connection axially movable in the plunger; a plunger valve actuated by said sucker rod connection; and devices forming a screw connection between the sucker rod connection and the standing valve, said devices being proportioned to the length of the plunger to prevent the closing of the plunger valve when said devices are screwed together.

19. In a pump, the combination of a working barrel; a standing valve in the working barrel; a plunger in the working barrel; a sucker rod connection axially movable in the plunger; a plunger valve actuated by the sucker rod connection; and a screw connection between the sucker rod

connection and the standing valve, comprising a yielding screw and a rod, the rod being of a length to hold the plunger valve open 25 when the devices are in engagement.

20. In a pump, the combination of a working barrel; a standing valve in the working barrel; a plunger; a sucker rod; a sucker rod connection axially movable in 30 the plunger; a plunger valve actuated by the sucker rod connection; a screw connection between the sucker rod connection and the standing valve; a trunnion carrying the sucker rod; and a screw connection between 35 the trunnion and the sucker rod.

In testimony whereof I have hereunto set my hand in the presence of two subscribing witnesses.

RUDOLPH CONRADER.
